ATTORNEY

UNITED STATES PATENT OFFICE

CORBON L. HARVEY, OF CLEVELAND, OHIO

RACK FOR LOOSE LEAF LEDGERS

Application filed March 11, 1932. Serial No. 598,123.

This invention relates to new and useful improvements in racks for loose leaf ledgers, the objects of the invention being the provision of a rack wherein the covers of the ledger are supported in substantially upright positions in spaced-apart relation, the ledger sheets or leaves being supported at their back edges between said covers and readily movable from one to the other, said rack being so arranged that said leaves are maintained at all times in proper alignment with each other, thereby facilitating the insertion of the ledger binding posts through the aligned apertures of said sheets.

Other objects of the invention are to provide a rack having a raised horizontally disposed platform for supporting the sheets and the back cover of said ledger in substantially upright positions, the rear wall of said rack being extended upwardly above said platform to form support for said back cover, the forward end of said rack being so arranged that the front cover is supported in substantially upright position on a horizontal plane arranged below said platform so that said front cover does not interfere with the reading or scanning of said sheets.

Still other objects of the invention are to provide a rack of the class described having a raised platform for supporting the sheets and the rear cover of the ledger in substantially upright position and having means for supporting the front cover in substantially upright position but suitable distance below the supporting surface of said sheets and said back cover, said rack being provided with guides for engaging the side edges of said sheets and maintaining them at all times in aligned positions, thereby facilitating the securing of said sheets between the ledger covers.

Further objects of the invention are to provide a rack for loose leaf ledgers having a raised platform for supporting the ledger sheets and the back cover thereof in substantially upright position and the front cover in a position spaced therefrom and occupying a lower position, said rack being provided with displaceable guides for engaging the side edges of said sheets and maintaining

them in properly aligned positions, said guides being provided with seats for engaging the ledger covers and holding them against displacement when in open position.

With these and other objects in view, my invention consists in certain novel features of construction and arrangement of parts, hereinafter more fully described and claimed, and illustrated in the accompanying drawing, in which—

Figure 1 is a side elevation of my improved rack showing the loose leaf ledger arranged in open position in dotted lines.

Figure 2 is a top plan view of my improved rack showing the guides in open or displaced positions.

Figure 3 is an enlarged vertical cross section taken on line 3—3 of Figure 1.

Figure 4 is a front end view of the platform showing the movable stop plate in dotted lines in raised position.

Figure 5 is an enlarged horizontal cross section taken on line 5—5 of Figure 1.

The ledger which is used in combination with my rack consists of a front cover A having binding posts B, a rear cover C having means for receiving and securing said posts, and loose leaf or ledger sheets D having their rear edges provided with notches or seats for engagement with said binding posts.

In the present invention the ledger sheets are supported in substantially upright positions, being slightly inclined rearwardly. Usually each ledger sheet has a heading located adjacent to the top edge and the body of this sheet is divided into a plurality of vertically disposed columns in which various items are inserted as each sale is made.

The rack consists of a base 10, a front end wall 11, a rear end wall 12, a platform 14, and side guides 15. The platform 14 is supported in raised position on base 10 in any suitable manner, and preferably by a front intermediate wall 16 and a rear wall 12. This intermediate wall 16 is spaced from wall 11, thereby providing a pocket 17, the bottom of which is formed by base 10. The platform 14 and the wall 16 are narrower than the widths of front and rear walls 11 and 12 and said end walls are connected together by side

walls 19 so that a space or pocket 20 is formed on each side of said platform 14. The upper edges of these side walls preferably terminate in a horizontal plane with the top of said platform 14 and said platform is covered with suitable material of cork or linoleum 21 so as to provide suitable working surface for said platform, as shown in Figure 3.

Side guides 15 are hinged to the top edges 10 of side walls 19 by means of hinges 22. Thus said guides can be moved into upright positions to engage the side edges of the ledger sheets and keep the latter properly aligned (see Figs. 1 and 3). Said guides can be moved into displaced or lower positions, as shown in full lines in Figure 2 and in dotted lines in Figure 3, so as to leave said platform open and to facilitate the positioning and removal of said ledger sheets.

20 When said guides occupy raised positions the distance between the inner faces thereof is substantially the same as the width of sheets D, so that the latter are held at all times in aligned positions. As the ledger covers A and 25 C are of greater widths than said sheets D, the rear end of each guide is provided with a notch 24 which when said guides occupy upright positions provide the necessary clearance for the corners of covers C and at the 30 same time serve to hold the latter against displacement.

The forward ends of said guides are provided with obliquely disposed grooves or seats 25 which when said guides occupy raised positions engage the edges of the front cover A and serve to hold the latter against displacement. Thus said guides in addition to their function of maintaining the sheets in proper relation with each other also serve to hold 40 the covers in proper relation with said sheets and against accidental displacement.

The rear end wall extends a suitable distance above platform 14, as indicated at 12a, and is provided adjacent to one side with a 45 flanged retaining member 26 which is adapted to receive and overlap the corresponding side edge of the rear ledger cover when the latter is placed on the rack. Thus a stop is provided for said cover so that the latter is accurately positioned and retained relatively to 50 said ledger leaves.

Each side wall 19 is provided near its forward end with an inwardly presented notch or recess 27 which permits the front cover A to enter pocket 17. In order to prevent the foremost ledger leaf when placed against cover A from slipping into pocket 17 a stop plate 28 is provided. This plate is slidably mounted in the intermediate wall 16 and 60 when in extended position, as shown in dotted lines in Figure 4, it projects above said platform surface 21 and forms a stop for the ledger leaves. The plate is provided with a suitable finger hold 29 by means of which it 65 can be manipulated and the wall 16 and plat-

form 14 are provided with a notch 30 and 31, respectively, which permit the manual engagement of finger hold 29.

In using the device, the covers A are disengaged from each other and placed in position shown in dotted lines in Figure 1. The ledger leaves are preferably placed against the cover A and are then placed against cover C as the operator gets through with each ledger sheet. The guides 15 being placed in upright positions serve to retain the covers in their proper positions and the ledger sheets D are maintained in proper alignment with each other so that when the operator is through with the ledger the binding post B can be readily placed in position without the necessity of manipulating the ledger sheets.

When the cover A occupies position in the rack the binding posts B are disposed in the side pockets 20, as shown in dotted lines in Figure 1, so that said binding posts do not interfere with the movement of said ledger sheets.

My improved rack is of simple construction, is so arranged that the ledger sheets can be moved from one cover to the other or removed from the rack, and both the covers and the ledger sheets are safely held in their proper positions on said rack.

I claim:

1. A rack for loose leaf ledgers comprising a raised platform for supporting the ledger leaves, a rear wall extending from said platform for supporting the rear cover of said ledger in substantially upright position, and a front wall spaced forwardly from said platform and extending below the latter for supporting the front cover in substantially upright position and on a horizontal plane a suitable distance below said platform.

2. A rack for loose leaf ledgers comprising a raised platform for supporting ledger leaves, a rear wall extending upwardly from said platform for supporting the rear cover of said ledger in substantially upright position whereby said ledger leaves can rest against said rear cover, a front wall disposed forwardly of and in spaced relation with the forward end of said platform for supporting the front cover of said ledger in substantially upright position and in spaced relation with said sheets and said rear cover.

3. A rack for loose leaf ledgers comprising a raised platform for supporting ledger leaves, a rear wall extending upwardly from said platform for supporting the rear cover of said ledger in substantially upright position whereby said ledger leaves can rest against said rear cover, a front wall disposed forwardly of and in spaced relation with the forward end of said platform for supporting the front cover of said ledger in substantially upright position and in spaced relation with said sheets and said rear cover, and means for engaging the side edges of said

ledger leaves and maintaining the latter in alignment with each other.

4. A rack for loose leaf ledgers comprising a raised platform for supporting ledger leaves, a rear wall extending upwardly from said platform for supporting the rear cover of said ledger in substantially upright position whereby said ledger leaves can rest against said rear cover, a front wall disposed forwardly of and in spaced relation with the forward end of said platform for supporting the front cover of said ledger in substantially upright position and in spaced relation with said sheets and said rear cover, means for engaging the side edges of said ledger leaves and maintaining the latter in alignment with each other, and a stop member on the rear wall of said rack for engaging one of the side edges of said rear cover and maintaining the latter in proper relation with said sheets.

5. A rack for loose leaf ledgers comprising in combination a raised platform for supporting the ledger leaves, a rear wall extending upwardly from said platform for supporting the rear cover of said ledger in substantially upright position, a front wall arranged in spaced relation with the forward end of said platform for supporting the front cover of said ledger in substantially upright position in spaced relation with said sheets, and a guide disposed longitudinally and in spaced relation on each side of said platform, said guides being movable into upward positions to engage the side edges of said ledger leaves and hold the latter in proper alignment with each other, said guides being movable downwardly below the plane of said platform so as to provide working clearance for said ledger leaves.

6. A rack for loose leaf ledgers comprising a raised platform for supporting ledger leaves, a rear wall extending upwardly from said platform for supporting the rear cover of said ledger in substantially upright position whereby said ledger leaves can rest against said rear cover, a front wall disposed forwardly of and in spaced relation with the forward end of said platform for supporting the front cover of said ledger in substantially upright position and in spaced relation with said sheets and said rear cover, a guide disposed longitudinally and in spaced relation on each side of said platform, said guide being hingedly mounted for movement into upward position to engage the side edges of said ledger leaves and of said ledger covers and maintain them in aligned relation with each other, said guides being movable downwardly below the top of said platform to permit manipulation of said ledger parts.

7. A rack for loose leaf ledgers comprising a raised platform for supporting ledger leaves, an end wall extending upwardly adjacent to each end of said platform for sup-

porting the ledger covers in spaced relation, and a horizontally disposed guide movably mounted adjacent to each side of said platform for engaging the side edges of said ledger leaves and maintaining them in aligned 70 relation.

8. A rack for loose leaf ledgers comprising a raised platform for supporting ledger leaves, an end wall extending upwardly adjacent to each end of said platform for supporting the ledger covers in spaced relation, and a horizontally disposed guide movably mounted adjacent to each side of said platform for engaging the side edges of said ledger leaves and maintaining them in aligned 75 80 relation, said guides being provided with seats for engaging the side edges of said covers and hold the latter against displacement.

In testimony whereof I hereunto affix my signature this 27th day of February, 1932. 85

CORBON L. HARVEY.
